INVENTOR

Seth Wheeler,

UNITED STATES PATENT OFFICE.

SETH WHEELER, OF ALBANY, NEW YORK.

TOILET-PAPER FIXTURE.

SPECIFICATION forming part of Letters Patent No. 341,709, dated May 11, 1886.

Application filed December 23, 1885. Serial No. 186,531. (No model.)

To all whom it may concern:

Be it known that I, SETH WHEELER, a citizen of the United States, and a resident of the city and county of Albany, in the State of New York, have invented certain new and useful Improvements in Toilet-Paper Fixtures, of which the following is a specification, reference being had to the accompanying drawings, forming part thereof.

10 This invention has reference to improvements in the fixture by means of which an oval roll of paper may have a determinate and sufficient amount of paper cut off from it each time the fixture is operated.

15 It consists in the combination, with the arms of a bracket-fixture, of a swing-frame carrying a knife-bar, and having rotation on a shaft connecting it with such arms, and a former for carrying an oval roll of paper placed on said 20 shaft and within said frame.

It further consists of certain details of mechanism hereinafter described.

In the drawings, Figure 1 represents a side view of a bracket-fixture containing an oval 25 roll of paper on its former, with the roll in position to be operated for the purpose of detaching a sheet of paper therefrom. Fig. 2 is a sectional view taken in the line $x-x$ of Fig. 1. Fig. 3 is a view of the former, upon which 30 the oval roll of paper is placed preparatory to its insertion in the oscillating frame, retained between the two bracketed arms of the fixture by means of a shaft, as seen in Fig. 2.

35 a is the bracket-fixture intended to be secured to a wall or partition, as shown by the screws in Fig. 2.

b b' are bracket-arms projecting out from said fixture.

40 c is a swing-frame placed between these arms b b' , carrying a serrated knife-bar, d .

45 e is a former of flat metal of sufficient length and width to enter the interior space or opening of an oval roll of paper, f . This former e has extending across it at its top edge a tube, g , through which is passed the shaft h after the former and roll of paper thereon have been placed in the frame c , thus securing the former e , the roll f , and the frame c to the bracketed arms b b' in bearings i i .

50 In one of the legs of the frame c is placed a projection, j ; which takes into one of the openings or slots j' of the former e . This is

in order to keep the frame c from shifting along the roll of paper as it is operated to detach a piece from the roll. The other opening or slot, j'' , at the top of the former is intended for the insertion of the fingers to grasp the shaft h after the paper has been used up from off the roll, for the purpose of releasing the former e from the frame c . The socket-opening, k 55 6c gives vertical space from one of the bearings i for the lifting up of the shaft h and pushing it out through the opening k' in the arm of the fixture, in order to release the former e from the frame c . This opening k' and vertical 6: socket-opening k down to the bearing i on one side of a bracket-fixture is old and well known and need not be further described.

The knife-bar d is placed high enough on the frame c , above the shaft h and its bearings, 7c to clear the outer surface of the roll of paper inserted underneath it. I prefer to make its edge serrated, as such has been found to better sever the paper.

75 The operation of this improved fixture is as follows: The former e is placed in a roll of paper, f . The roll is then placed within the frame, which brings the projection j into one of the notches, j' , of the former. The shaft h is then inserted through the opening k' of the 8c bracket b into the openings c c' of the frame c until it drops into the bearings i i of the arms b b' of the bracket-fixture. The paper is then taken hold of at l by the hand and drawn down, which causes the roll with the frame c 85 to rotate on the shaft h until it assumes the position as seen in dotted lines of Fig. 1. This also brings the knife-edge d into the position also seen in dotted lines in that figure, thereby causing the severance of a portion of the paper. Immediately upon this severance of the paper the roll will fall back into its original position, as the larger part of it is above the shaft h , which also brings into its original position the knife-bar d on the frame c . 9c 95

Many advantages result from this construction and mode of operation, some of which are simplicity of arrangement, and of being able to obtain a sufficient amount of paper for use, notwithstanding the roll is nearly used up. 100 This is not the case when the arrangement of fixture adapted to a round roll is used, for each revolution of the round roll, when it is reduced to about one-half its quantity, prac-

tically gives sheets too short for use, thus rendering such other fixtures to a large extent practically useless. Another advantage is that this fixture and its contained roll of paper 5 occupy less space on the wall in use.

I claim—

1. The combination, with the arms of a bracket-fixture, of the shaft *h*, having its bearings in the said arms, a former, *e*, for carrying 10 an oval roll of paper, formed at its upper edge into a tube through which the shaft *h* passes, and having openings or slots *j*', the swinging frame *c*, having knife-bar *d* mounted and rotating on shaft *h*, and provided with projection *j*, substantially as and for the purpose 15 described.

2. The combination, with a bracket having arms *b b'*, one of which is provided with openings *k k'*, of a swinging frame, *e*, having openings *c c'*, and provided with a knife-bar, *d*, an 20 oblong former, *e*, for carrying an oval roll of paper, said former being provided at the top with a tube, *g*, and slot *j''*, and the shaft *h*, passed loosely through the openings *k k' c c'* and tube *g*, and detachably supported in bearings 25 in the ends of the bracket-arms, substantially as described.

SETH WHEELER.
